CLAIM

The ornamental design for a belted package for folding spoons, as shown and described.

DESCRIPTION

FIG. 1 is a perspective view of a belted package for folding spoons showing my new design; it is being understood that the spoon pattern is repeated uniformly throughout the belt;

FIG. 2 is an enlarged scale partial front elevational view thereof;

FIG. 3 is a rear elevational view of FIG. 2;

FIG. 4 is a top plan view of FIG. 2;

FIG. 5 is a bottom plan view of FIG. 2; and,

FIG. 6 is a left side elevational view of FIG. 2; the right side elevational view being a mirror image thereof.

FIG.1

FIG.2

FIG. 3

FIG. 4

FIG. 5

FIG. 6
